US0D1104969S

(12) **United States Design Patent** (10) **Patent No.:** **US D1,104,969 S**
(45) **Date of Patent:** **** Dec. 9, 2025**

(54) **CHARGER**

- (71) Applicant: **SHENZHEN LVCHEM TECHNOLOGY CO., LTD.**, Guangdong (CN)
- (72) Inventors: **Yang Cui**, Guangdong (CN); **Yufeng Chen**, Guangdong (CN); **Xianmiao Luo**, Guangdong (CN); **Chang Yang**, Guangdong (CN)
- (73) Assignee: **SHENZHEN LVCHEM TECHNOLOGY CO., LTD.**, Shenzhen (CN)
- (**) Term: **15 Years**
- (21) Appl. No.: **30/008,199**
- (22) Filed: **Jun. 13, 2025**

Related U.S. Application Data

- (62) Division of application No. 29/993,497, filed on Mar. 14, 2025.
- (51) **LOC (15) Cl.** **13-02**
- (52) **U.S. Cl.**
USPC **D13/108**

(57) **CLAIM**

The ornamental design for a charger as shown and described.

DESCRIPTION

FIG. 1 is a perspective view of a charger showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the charger where the charger is in a configuration of use.

The broken lines in the drawings depict portions of the charger that form no part of the claimed design.

1 Claim, 9 Drawing Sheets
